UNITED STATES PATENT OFFICE.

JOHN A. McGINNIS, OF WHEELING, WEST VIRGINIA, ASSIGNOR TO WHEELING STAMPING COMPANY, OF WHEELING, WEST VIRGINIA, A CORPORATION OF WEST VIRGINIA.

MACHINE FOR THE MANUFACTURE OF COLLAPSIBLE METAL TUBES.

Application filed June 22, 1921. Serial No. 481,042.

To all whom it may concern:

Be it known that I, JOHN A. McGINNIS, a citizen of the United States, residing at Wheeling, in the county of Ohio and State 5 of West Virginia, have invented a new and useful Improvement in Machines for the Manufacture of Collapsible Metal Tubes, of which the following is a full, clear, and exact description, reference being had to the 10 accompanying drawings, forming part of this specification, and in which—

Figure 1 is a side elevation, partly broken away, of a machine embodying my invention;

15 Figure 1^a is a diagram illustrating the different operations performed by the machine;

Figure 2 is a view, partly in side elevation and partly in vertical section, showing certain parts of the machine;

20 Figure 3 is a detail view showing the cap holding chuck and adjacent parts in vertical section;

Figure 4 is a face view of the chuck;

25 Figure 5 is a plan view showing certain of the parts on a larger scale;

Figure 6 is a view, partly in side elevation and partly in vertical section, of the chuck and the parts for feeding the caps into 30 the chuck;

Figure 7 is a fragmentary view in vertical section, showing the lower portion of the feeding chute;

Figure 8 is a plan view of the chuck and 35 adjacent parts;

Figure 9 is a view partly in side elevation and partly in vertical section;

Figure 10 is a detail sectional view showing one of the cutter holders; and

40 Figure 11 is a perspective view of the cutter carrier.

My invention has relation to machines for the manufacture of collapsible metal tubes; and, more particularly, to the provision of 45 mechanism in the nature of an attachment to the machines which are commonly used for the purpose of cutting the formed tubes to length, trimming the neck ends of the same, and threading the necks, such attachment

operating to attach the cap closures to the 50 necks after they have been threaded.

Heretofore, as far as I am aware, it has been customary to screw the caps onto the threaded necks of the tubes after the latter 55 have been removed from the threading and trimming machines.

The nature of my invention will be best understood by reference to the accompanying drawings, in which I have shown my invention as applied to a tube trimming and 60 threading machine of well known character, and which will now be described, it being premised, however, that various changes can be made in the details of construction, arrangement and combination of the various 65 parts without departing from the spirit and scope of my invention as defined in the appended claims.

In these drawings, the numeral 2 designates the frame of a tube cutting and trimming machine. This machine is provided with a rotary mandrel-carrying turret which is designed to have a step-by-step rotation and which carries four tube-holding mandrels 3, each of these mandrels being independently rotatable about a horizontal axis. 70 4 designates the driving shaft of the machine; and 5 the actuating gears for the turret and mandrels. Machines embodying 75 the parts just referred to are well known in the art and need not be described in detail.

In operation, each mandrel has four operative positions. In one position, the collapsible tube to be trimmed and threaded is placed on the mandrel; at the next position 80 the neck is trimmed and threaded; at the third position the open end of the tube is cut to length; and at the fourth position the tube is removed. My invention adds a cap attaching operation at the third position of each mandrel. These several positions of the mandrels are best illustrated in the diagram of Figure 1^a.

6 designates a feed hopper in which a mass of the threaded and finished caps to be 85 applied to the collapsible tubes are placed. This hopper is of any well known selective character and acts to feed the caps with

their open sides uppermost into a suitable delivery chute 7. This chute is provided with the overflow spout 8 which discharges any excess of caps fed over and above the requirements of the machine.

The threaded caps pass downwardly in the chute towards its lower end, where their delivery is controlled by means of a series of reciprocating gates 9, 10, and 11- (see Figs. 6 and 7). These gates project in spaced relation into the lower portion of the chute 7 from opposite sides thereof, the arrangement being such that when the upper and lower gates 9 and 10 are across the passage of the chute, the gate 11 is withdrawn from such passage, and vice versa. The gates are mounted on a carriage 12 which is arranged to be reciprocated horizontally by means of a lever 13 pivoted at 14 and 20 having its other arm provided with a cam slot 14^a, which is engaged by a stud 14^b on a member 15 which is rigidly connected to a reciprocating member 16 hereinafter more fully described. By the operation of 25 these gates, the caps are delivered singly, in succession, from the lower end of the chute 7, in edgewise position (see Fig. 6) where they are received in a cavity 17 formed in a guide member 18, the top wall 30 of this guide member being cut away as shown at 18^a (see Figs. 6, 7, and 8) to allow the caps to fall through into said cavity. 19 designates the outer member of a chuck into which the caps are inserted from the 35 cavity 17, and which holds them while they are being threaded upon the tubes. The holding member of the chuck comprises a helical wire coil 20 bent into annular form, with its inner diameter of proper size to 40 receive and frictionally hold the cap. This coil is seated in a bushing 21 which is seated in the outer member 19. This bushing and the coil 20 are normally held against rotation in the member 19 while the cap is being attached, but are capable of rotation 45 therein when necessary, as when the cap has been fully seated upon the tube. This is effected by means of the two friction members 22 (see Fig. 4), which bear against 50 the outer surface of the bushing 21 under the action of an adjustable spring 23.

The opening in the chuck is opposite the end of the mandrels 3 when the latter are in their third position shown in Fig. 1^a. 55 The outer member 19 of the chuck is attached to or formed as a part of a sleeve member 24, which is mounted to be moved endwise toward and away from the mandrels. This endwise movement is effected through the rod 25 having a sliding bearing in the fixed guide member 26, and which is connected through the springs 27 with an actuating arm 28. This arm 28 is rigidly attached at its lower end to the 60 usual slide 29, which carries a trimming

cutter 30 for trimming off the neck ends of the tubes. The member 24 is further guided in its movement by being mounted upon the sleeve 31, seated in the guide member 26, and further held by a pin 32 70 secured in the lower portion of the feed chute 7 and extending upwardly through a slot 33 in the member 24.

The caps are moved from the cavity 17 into the chuck by the action of a plunger 75 34 whose rod 16 is slidably mounted in the sleeve 31 just referred to, and which is rigidly connected to the actuating arm 28 before described. It is to this plunger rod 16 that the actuating connections for the 80 gate devices are connected, as before described.

35 and 36 designate the threading cutters for the tube necks, these cutters being frictionally rotated by contact with the rotating necks of the tubes, and being geared together through the gears 36^a (see Fig. 2) in the usual manner. The cutters are mounted on the levers 37, these levers being moved to cause the cutters to approach towards 90 and recede from each other by the arm 38 actuated by the lever 39, which in turn is actuated by the stud 40. The stud 40 is in turn actuated by the cam 41 on the shaft 42, which is driven by the gearing which 95 actuates the turret and spindles.

The slide 29 which carries the cutter 30, before referred to, is reciprocated in the usual manner by the stud 43 (see Fig. 9) carried by the slide and engaging the cam 100 groove 44 of a cam 45 which is mounted on the shaft 41. This slide is reciprocated towards and away from the ends of the mandrels in unison with the movement of the plunger 34 and chuck carrier 24, so as 105 to bring the cutting edge of the tool 30 into trimming contact at the proper time with the neck ends of the tubes when they are in the second position indicated in Figure 1^a. It is desirable that means be provided for very accurately positioning the cutter 30. For this purpose, said cutter is secured in a holder 46 which has a T-head 47 which is adjustably secured by means of the set screws 48 in the T-slot of the head of 110 a carrier 49. This carrier 49 is secured in the slide 29^a by means of a screw 50 which permits of longitudinal adjustment of the carrier by loosening the screw.

The shaft 42 is extended to the left (looking at Fig. 1) and carries a pulley 51 which, by means of a belt 51^a, drives the gears 52 which rotate the cap hopper 6.

53 designates the usual cutter which cuts the tubes to length, at the third position of 125 the mandrels.

The operation is as follows. The tubes are placed upon the mandrels by an attendant, a tube being placed on each mandrel as it comes to the first position indicated in Fig. 130

ure 1^a. At the second position, the cutters 35 and 36 are moved by the lever 39 into cutting relation to the neck of the tube, and act to exteriorly thread such neck. At the same time, the cutter 30 is actuated to trim off the end of the neck and thus open the usual discharge slot therein. At the third position, the rod 16 is first moved independently of the rod 25, while the arm 28 is moving from the full line position to the dotted line position shown in Figure 6, to cause the plunger 34 to force a cap from the cavity 17 into the chuck 20, and thereafter the chuck carrier 24 is moved with the plunger 34 to cause the chuck to move from the full line position to the dotted line position shown in dotted lines in Figure 6, and thus engage the open end of the cap in the chuck with the end of the threaded neck of the collapsible tube, indicated in said figure. The rotation of the tube with its mandrel then causes the cap to be threaded upon said neck, after which the chuck returns into position to receive another cap, the chuck readily disengaging itself from the cap which has been attached. At the fourth position, the tube is removed by the attendant. These operations are repeated successively upon the tube of each mandrel.

30 The advantages of my invention will be apparent. It is readily applicable to existing machines, the only change necessary being the extension of the shaft 42 to form a driving means for the hopper, and the attachment of the arm 28 to the cutter carrying slide 29. The parts constituting the invention are of simple character and construction, and their operation is reliable. The caps are attached to the tubes in the proper manner before the latter are removed from the machine, thus doing away with the necessity for a subsequent manual operation for this purpose. The cap holding chuck described is peculiarly effective in the provision of the spring coil which forms an efficient frictional holder for the caps, having the desired degree of resilience. The frictional device for controlling the rotation of the coil holder is also an advantageous feature.

50 It will be obvious that many changes can be made in the details of the construction and arrangement of the parts. Thus, any suitable type of selective feeder may be employed; the details of the mechanism for causing the caps to be delivered to the chuck may be changed; and various other changes may be made.

I claim:

60 1. The combination with a machine for threading the necks of collapsible metal tubes and for trimming the tubes, of cap feeding and attaching devices operating in co-relation with the threading and trimming devices, to apply caps to the thread-

ed necks of the tubes while the tubes are still on the machine, substantially as described.

2. The combination with a machine for threading the necks of collapsible metal tubes and for trimming the tubes, of cap feeding and attaching devices operating in co-relation with the threading and trimming devices, to apply caps to the threaded necks of the tubes while the tubes are still on the machine, said cap applying operation being coincident with the trimming operation of the machine, substantially as described. 70

3. The combination with a machine having means for trimming and threading collapsible tubes, said machine having a rotary mandrel for holding the tubes while they are being trimmed and threaded, of a cap feeding and attaching device cooperating with the said mandrel for attaching caps to the threaded ends of the tubes; substantially as described. 80

4. The combination with a machine having means for trimming and threading collapsible tubes, said machine having a rotary mandrel for holding the tubes while they are being trimmed and threaded, of a cap feeding and attaching device co-operating with the said mandrel, said mandrel having a plurality of operating positions, and the cap attaching operation taking place when the mandrel is at one of said positions, substantially as described. 90

5. The combination with a machine having means for trimming and threading collapsible tubes, said machine having a rotary mandrel for holding the tubes, means for rotating the mandrel about its own axis and also for turning it about another parallel axis, of a cap feeding and attaching device co-operating with said mandrel, substantially as described. 100

6. A cap feeding and attaching mechanism for collapsible tube machines, comprising a selective feeder which delivers the caps in a definite predetermined position, a feed chute into which the caps are delivered from the hopper, a chuck for holding the caps while they are being attached, and means for periodically inserting the caps into the 110 chuck as they are delivered from said chute, substantially as described.

7. A cap feeding and attaching mechanism for collapsible tube machines, comprising a selective feeder which delivers the caps in a definite predetermined position, a feed chute into which the caps are delivered from the hopper, a chuck for holding the caps while they are being attached, and means for periodically inserting the caps into the 120 chuck as they are delivered from said chute, said chute having gates for separating the caps in the chute and controlling their delivery therefrom, substantially as described. 125

8. A cap feeding and attaching mechanism for collapsible tube machines, comprising a selective feeder which delivers the caps into a definite predetermined position, 5 a feed chute into which the caps are delivered from the hopper, a chuck for holding the caps while they are being attached, and means for periodically inserting the caps into the chuck as they are delivered 10 from said chute, said chute having oppositely acting separated gates, and means for actuating the gates in timed relation to the other operations of the machine, substantially as described.
- 15 9. In mechanism of the character described, the combination with a feed chute, of a chuck into which the caps are delivered from said chute, said chuck having a cap holder consisting of a helical metal coil bent 20 into ring form, substantially as described.
10. In mechanism of the character described, the combination with a feed chute, of a chuck into which the caps are delivered from said chute, said chuck having a 25 cap holder consisting of a helical metal coil bent into ring form, together with a rotatable sleeve in which said holder is seated, and a friction device for the sleeve, substantially as described.
- 30 11. In mechanism of the character described, the combination with a feed chute, of a chuck into which the caps are delivered from said chute, said chuck having a cap holder consisting of a helical metal coil 35 bent into ring form, together with a rotatable sleeve in which said holder is seated, and an adjustable friction device for the sleeve, substantially as described.
12. In mechanism of the character described, the combination with a feed chute 40 having means for delivering caps in definite predetermined positions, of a chuck carrier mounted to reciprocate below the discharge end of said chute, a cap holding chuck on 45 said carrier adjacent the lower end of said chute, a plunger for moving the caps from the lower portion of the chute into the chuck, means for periodically reciprocating the plunger, and means for periodically reciprocating the carrier, substantially as described.
13. In mechanism of the character described, the combination with a feed chute 50 having means for delivering caps in definite predetermined positions, of a chuck carrier mounted to reciprocate below the discharge end of said chute, a cap holding chuck on 55 said carrier adjacent the lower end of said chute, a plunger for moving the caps from the lower portion of the chute into the chuck, means for periodically reciprocating the plunger, and means for periodically reciprocating the carrier, substantially as described.
14. In mechanism of the character described, the combination with a tube holding mandrel, of a feed chute for the caps, feeding means for delivering them in definite predetermined positions, a chuck carrier mounted to reciprocate below the discharge 75 end of said chute and having a cap receiving cavity therein, a cap holding chuck on said carrier adjacent to said cavity, a plunger for moving the caps from the cavity into the chuck, means for periodically reciprocating said plunger, and means for periodically reciprocating the carrier, substantially as described.
15. In mechanism of the character described, the combination with a machine having a tube holding mandrel adapted to 80 prevent collapse of the tube, of a cap holding chuck adapted to cooperate with the mandrel, means for periodically feeding a cap into said chuck, and means for periodically moving the chuck toward and away 85 from the mandrel, substantially as described.
16. In a machine of the character described, the combination with a rotary mandrel, of a chuck for frictionally holding a cap, feeding mechanism for delivering the 90 caps in predetermined positions and at predetermined intervals, means for inserting the caps as they are fed into the chuck, and means for periodically causing the mandrel and chuck to relatively approach towards 95 and recede from each other, substantially as described.
17. In a machine of the character described, the combination with a tube holding mandrel, of a cutter device for trimming the neck ends of the tubes, means for moving said cutter device towards and away 100 from the mandrel, and cap feeding and attaching means actuated by the movements of the cutter carrier, substantially as described.
18. In a machine of the character described, a cutting tool for trimming the neck ends of the mandrel, a holder in which the tool 105 is secured, a carrier in which the tool holder is secured, means for adjusting the carrier longitudinally, means for adjusting the holder in the carrier and means for attaching a cap to the trimmed neck, substantially as described.
19. In a machine of the character described, the combination with a tube holding mandrel, of a cutter device for trimming the neck ends of the tubes, means for moving said cutter device toward and away from the mandrel, and cap feeding and attaching 115 means for attaching a cap to the trimmed neck ends of the tubes, substantially as described.
20. The combination with a machine for threading the necks of collapsible metal 120

- tubes, of means for frictionally engaging, holding and applying caps to the threaded necks of the tubes while the tubes are still on the machine, substantially as described.
- 5 21. In a collapsible tube working machine, means for threading the necks of the tubes, and means for automatically supplying caps to the threaded necks, substantially as described.
22. In a collapsible tube working machine, 10 means for threading the necks of the tubes, and means for frictionally holding caps and applying the same automatically to the threaded necks, substantially as described.
- In testimony whereof, I have hereunto set 15 my hand.

JOHN A. McGINNIS.
